UNITED STATES PATENT OFFICE

LOUIS L. DRIGGS, JR., OF NEW ROCHELLE, AND HENRY B. FABER, OF NEW YORK, N. Y.

PHOTOGRAPHIC-FLASH-LIGHT CARTRIDGE

Application filed January 8, 1929. Serial No. 331,128.

Our present invention relates to improvements in apparatus for taking flash-light pictures, and it is intended to provide a cheap, simple, efficient and convenient arrangement which can be used with safety and without the necessity for installing complicated apparatus or manipulation in the preparation of the parts just prior to the time that the flash-light is used.

10 Our invention comprises the mounting of all the essential parts together for the quick and efficient flash-light for photographic purposes in a single cartridge case which may be safely stored away or transported from place to place until, at the moment of use, it is fired from a pistol or other convenient firearm, for instantaneous photography.

The invention will be more fully understood after reference to the accompanying drawings, in which like parts are indicated by similar reference symbols throughout the several views, and in which

Figure 1 shows a longitudinal section through a cartridge case, showing the illuminating charge of flashlight powder mounted in front of an air chamber and intended to be ignited and expelled by a blank cartridge which is fired into said air chamber.

Figure 2 is a similar view to Figure 1 and shows a modification in which the blank cartridge is supplemented by an ignition and ejecting charge.

Figure 3 is a detail showing the container for the flash-light composition, and with the air chamber in rear thereof, shown in Figure 2.

Figure 4 shows a modification of Figures 2 and 3, in which the container for the flash-light powder contains a layer of oxygen bearing material kept out of contact with the illuminating powder until after the cartridge is fired.

Referring first to the construction shown in Figure 1, A represents a metal cartridge case 45 preferably provided with the annular groove a, whereby the cartridge case may be retained within the barrel of the firearm from which the cartridge is fired.

Such a cartridge may be fired from a muzzle-loading firearm, such as is shown in our

application Ser. No. 263,024, filed March 20, 1928, and entitled Improvements in firearms, in which device there is a spring latch engaging the annular groove in the cartridge case.

55 In this form of device, the cartridge case is provided with a head a', in which the blank cartridge B is held. This cartridge case is also provided with an inwardly projecting annular shoulder a² against which the end of the cylindrical container C engages. Spaced apart from the blank cartridge B is a sup-shaped head D cut away as at d and to which the inflammable diaphragm D' is secured. In front of this head D, the flash light composition is mounted. This may consist of any suitable magnesium or other flash-light powder, and the front end of the container C is closed with the head D². This container C is slipped into the cylindrical portion a³ of the cartridge case, and then the front end of the cartridge case is crimped over as at a⁴, holding the container firmly in place in the cartridge case and leaving an air chamber between the head D and the rear head a' of the cartridge case. When the blank cartridge B is ignited, as by firing a small arm, the flame flies forward, and the powder gases expand in the air chamber and blow the flash-light powder forward. Shortly after the flash-light powder 60 is ejected from the cartridge case, it will be ignited by the flame burning away the inflammable diaphragm D, and there will be 65 instantaneous combustion, producing for 70 a brilliant light.

75 The interposition of the air chamber enables the flash-light powder to be ejected from the cartridge case and scatter widely in the air before the instantaneous and complete ignition takes place, so that there is no retarded burning, as occurs when a mass of flash-light powder is ignited from one side or surface only, as when using the flash-light powder in a pan.

80 In the form of device shown in Figures 2 and 3, the cartridge may be loaded into a breech-loading firearm, such as is shown in our application Ser. No. 263,025, filed March 20, 1928, and entitled Improvements in firearms, but obviously the cartridge case may 85 90 95 100

be fitted for use with either a muzzle loading or breech loading piece.

In the form of device shown in Figures 2 and 3, the rear end of the cartridge comprises a paper head F secured in a metal cup G which projects forward in the form of a hollow cylinder, as at g, and is pressed inward, as at g', to form a seat for the primer H. Between the head F and the cylinder g the cylindrical shell I is mounted, which may be 10 of either metal or paper, and the front end of this shell is crimped inward, as at i, to hold in place the tube J, in which tube is mounted the container K having the heads k and k', between which heads the flash-light powder E is mounted. These heads k and k' are 15 preferably made of celotex or other inflammable material. In rear of the container K is the annular ring M having a head m, forming a cylindrical cup, or air chamber.

In rear of the head k and in rear of this diaphragm m, the igniting and ejecting charge N is mounted. This charge N is ignited by the primer or cap H, and when ignited it will expand into the air chamber M and will blow 20 out the illuminating charge E, igniting same about the same time that the illuminating charge in the dispersion cone clears the muzzle of the cartridge. In the form of device 25 shown in Figure 4, the parts are similar to those already described with reference to Figures 2 and 3, except that in the tube J and in addition to the illuminating charge and the air chamber already referred to, we provide 30 a body of oxygen bearing material, such as potassium chlorate, which may be held in a cylindrical cup P closed by the inflammable diaphragm p. When the primer H is fired, the igniting and expelling charge N will 35 expand in the air chamber M, and then will force the oxygen bearing material to mix 40 intimately with the illuminating powder E; and the two, being mixed together by the firing of the piece and dispersed as previously 45 described, will become ignited in a dispersed cone after leaving the cartridge case, producing an intense and instantaneous light. This 50 light will be much more intense, owing to the instantaneous character than would occur if the oxygen bearing material or the illuminating powder were not thoroughly mixed and in the widely dispersed condition at the instant of illumination.

By having the illuminating powder E, 55 which may be of any type of magnesium, or of any other illuminating powder, kept separate from the oxygen bearing material, which may be chlorate potash or the like, the danger from deterioration or premature explosion, which is experienced when these two are 60 kept mixed together or in contact with each other for any length of time, is avoided.

The regulations with regard to the manufacture or use of these flash-light powders 65 provide that the oxygen bearing material

shall not be kept mixed with the metal illuminating powder, but the mixture shall only be mixed just before the actual operation of using the flash-light powder; but by having the oxygen bearing material kept separate from and in rear of the illuminating material, the quick and efficient mixing of these at the moment of firing is secured. At the same time, the layer of oxygen bearing material serves to delay the ignition of the mixture until the mass has been finely divided and widely dispersed after leaving the mouth of the cartridge case, with the result that there will be a brief but intense flame.

By firing the illuminating powder from 80 the cartridge as described, we have found that there is a wide dispersing of an intensely brilliant flame due to the instantaneous and complete combustion of the mass. This enables us to get better results without increasing 85 the charge of flash-light powder and equal results by the use of a smaller charge of flash-light powder.

We do not mean to limit the invention to any particular kind of flash light powder 90 or any particular kind of oxygen bearing material, as these are well known in the art and are not a part of our present invention. While we have described embodiments of the invention in the preferred forms, it will be 95 obvious that various changes might be made in the construction, combination and arrangement of parts, which could be used without departing from the spirit of our invention, and we do not mean to limit the invention to such details, except as particularly pointed out in the claims.

Having thus described our invention, what we claim and desire to secure by Letters Patent of the United States is:—

1. A cartridge for use in flash-light photography comprising a cartridge case with an expelling and igniting charge mounted in the rear end thereof, an air chamber in front of said charge, a charge of oxygen bearing material in front of said air chamber, and a container containing flash light powder, mounted in said cartridge case in front of said oxygen bearing charge, with frangible diaphragms forming the heads of said container.

2. A cartridge for use in flash light photography comprising a cartridge case with an expelling and igniting charge mounted in the rear end thereof, an air chamber in front of said charge, a charge of oxygen bearing material in front of said air chamber, and a container containing flash light powder, mounted in said cartridge case in front of said oxygen bearing charge, with frangible diaphragms forming the heads of said container, the rear head of the container being also of combustible material.

3. A cartridge for use in flash light photography comprising a cartridge case with an expelling and igniting charge mounted in the

- rear end thereof, an air chamber in front of said charge, and a container containing flash light powder, mounted in said cartridge case in front of said air chamber, with diaphragms forming the heads of said container. 5

4. A cartridge for use in flash light photography comprising a cartridge case with an expelling and igniting charge mounted in the rear end thereof, an air chamber in front of said charge, and a container containing flash light powder, mounted in said cartridge case in front of said oxygen bearing charge, with diaphragms forming the heads of said container, the rear head of the container comprising also of combustible material. 10

5. A cartridge for use in flash light photography comprising a cartridge case with an expelling and igniting charge mounted in the rear end thereof, an air chamber in front of said charge, a cylindrical tube surrounding said air chamber, a charge of oxygen bearing material mounted in said tube in front of said air chamber, and a container containing flash light powder, mounted in said tube in front of said oxygen bearing charge, with frangible diaphragms forming the heads of said container. 15

6. A cartridge for use in flash light photography comprising a cartridge case with an expelling and igniting charge mounted in the rear end thereof, an air chamber in front of said charge, a cylindrical tube surrounding said air chamber, a charge of oxygen bearing material mounted in said tube in front of said air chamber, and a container containing flash light powder, mounted in said tube in front of said oxygen bearing charge, with frangible diaphragms forming the heads of said container, the rear head of the container being also of combustible material. 20

7. A cartridge for use in flash light photography comprising a cartridge case with an expelling and igniting charge mounted in the rear end thereof, a cylindrical tube contained in said cartridge case, a charge of oxygen bearing material mounted in said tube, and a container containing flash light powder, mounted in said tube in front of said oxygen bearing charge, with frangible diaphragms forming the heads of said container. 25

8. A cartridge for use in flash light photography comprising a cartridge case with an expelling and igniting charge mounted in the rear end thereof, a cylindrical tube enclosed in said cartridge case, a charge of oxygen bearing material mounted in said tube, and a container containing flash light powder, mounted in said tube in front of said oxygen bearing charge, with frangible diaphragms forming the heads of said container, the rear head of the container being also of combustible material. 30

9. A cartridge for use in flash light photography comprising a cartridge case provided with an igniting and expelling charge

in the rear end thereof, an air chamber in front of said charge, and a charge of flash light powder in front of said air chamber. 35

10. A cartridge for use in flash light photography comprising a cartridge case provided with an igniting and expelling charge in the rear end thereof, an air chamber in front of said charge, a charge of oxygen bearing material mounted in front of said air chamber, and a charge of flash light powder mounted in front of said oxygen bearing charge. 40
